UNITED STATES PATENT OFFICE.

DAVID D. GORDON, OF CHICAGO, ILLINOIS, ASSIGNEE TO STACKHOUSE & ALLEN, OF CHICAGO, ILLINOIS, A PARTNERSHIP CONSISTING OF JOHN H. STACKHOUSE AND JOHN R. ALLEN.

SWITCH MECHANISM.

Application filed April 11, 1921. Serial No. 460,283.

To all whom it may concern:

Be it known that I, DAVID D. GORDON, a citizen of the United States, residing at Chicago, in the county of Cook and State 5 of Illinois, have invented a certain new and useful Improvement in Switch Mechanisms, of which the following is a full, clear, concise, and exact description, reference being had to the accompanying drawings, forming 10 a part of this specification.

My invention relates to mechanical movements and has for its object the provision of a mechanism for performing a certain function which, for instance, is of particular utility in connection with switching devices.

In the application herein I will describe the movement more particularly as applied to a switching device of the wall type, it 20 being an object of this invention to provide a switching device of this character in which the circuit shall be made and broken by snap action.

My invention concerns itself particularly 25 with the provision of a snap action movement of this character in which a minimum number of parts are utilized to effect the definite result of moving the switch controlling element by snap action into its alternate positions.

In the form of the invention herein shown, the switch controlling element is pivotally mounted and means are provided to cause its snap action movement in alternate directions.

I will describe one form which my invention may take more in detail by referring to the accompanying drawing, in which

Fig. 1 is a front view of a switch structure constructed in accordance with my invention;

Fig. 2 is a partial longitudinal sectional view illustrating the same;

Fig. 3 is an enlarged detail view of the 45 moving parts;

Fig. 4 is a similar view showing the parts about to change their position by snap action; and

Fig. 5 is an end view of the switch movement proper removed from its containing insulating casing.

In the drawing as shown I provide the metallic outlet box 23 into which the switch structure carried within the insulating casing 24 is to be placed. A bridge or strap

25 carries the switch structure and is fastened to the casing 24 by the screws 26. This bridge is then utilized by means of its extremities 27 to secure the entire structure within the outlet box 23 by means of 60 the screws 28. The extremities of the bridge 25 are provided with bayonet slots 29 as shown more clearly in Fig. 1 so that it is not necessary to remove the screws 28 in order to insert the switch structure in place. 65 A very simple method is thus provided for inserting this switch movement into its position in the outlet box. A cover plate 30 is indicated in dotted lines to complete the entire structure. 70

The switch movement itself which is mounted within the casing 24 is designed to move by snap action a switch element 31 through the agency of the push buttons 32 and 33. This switch structure includes 75 two arms 34, 34 riveted to the bridge piece 25, which arms support a rotatable spindle or shaft 35. The arms 34 also pivotally support by means of their hook extremities 36 a C-shaped oscillating element 37 to 80 which is insulatingly fastened by means of the bracket 38 the double switch spring 39 so that this switch spring moves with the oscillating element 37. Suitable instrumentalities are interposed to effect a snap action movement of this element 37, and consequently the springs 39, first in one direction and then in the other, in order that contact may be established between the terminals 40 and 41 or the contact therethrough 85 broken, both by snap action. The buttons 32 and 33 are pivotally supported by an oscillating bridge piece 42 which is pivoted on the shaft 35, and which has arms 43 extending parallel to the arms 34. The buttons 32 and 33 which carry attaching elements 44 each have fingers 45 to limit their movement by their engagement with the bridge piece 25. The oscillating bridge piece 42 has projections 46 by means of 90 which it is pivotally engaged between arms of the engaging elements 44. A shifting C-shaped element 47 is slidably mounted within the element 37 through the agency of a spindle or shaft 48 carried by the element 47 which slides in grooves 49 provided in the C-shaped element 37. A spring 50 is mounted between the spindles 35 and 48 and tends to draw them closer together. The element 37 has fingers 51 which at times 105

are engaged by the arms 43, this engagement being just prior to the snap action movement of the element 37 from one alternative position to the other. The element 47 is pivoted to the element 43 as shown at 52, through the agency of fingers bent from the element 47 and engaging apertures in the arms 43.

It will be seen, for instance, by referring 10 to Fig. 3 that as the button 33 is pushed inwardly to move the element 37 from one limiting position to the other, that the swinging part of bridge piece 42 is rotated in a clockwise direction, thereby rotating its arms 43 about the shaft 35. This clockwise movement of the arms 43 swings the element 47 in a counterclockwise direction on account of the pivotal engagement at 52, and this element 47 in being swung 15 about its pivot 48 must also shift its position longitudinally by having the shaft 48 slide in the groove 49. This movement, of course, stretches the spring 50 and this stretching movement continues until the 20 pivotal point 52 has passed beyond the center line of the shafts 35 and 48, at which time the spring 50 is permitted to contract, thereby drawing the element 47 with its shaft 48 toward the right along the slot 49 until 25 the shaft 48 reaches the right hand extremity of this slot (Fig. 4). At the same time the rounded left hand extremity of the arm 43 has engaged the upper finger 51 of the element 37, thus pushing this element 37 30 in a counterclockwise direction to move the shaft 48 slightly beyond the line joining the shaft 35 and the pivotal point of this element 37. The spring 50 is thereupon in a position to still further contract and rapidly pull this element 37 in a counterclockwise 35 direction by snap action into its alternative position.

From what has been set forth the nature 40 of my said invention will be readily apparent to those skilled in the art, and also that it is capable of a great variety of uses and modifications without departing from its spirit. Having, however, thus described one form which my invention may take, 45 what I claim as new and desire to secure by Letters Patent is:

1. A device of the character described 50 comprising a pivoted control member, a pivoted switch operating member, and means interposed between said control member and said switch operating member for controlling the snap action movement of said switch operating member in both directions when said control member is moved, said means including a spring and a shifting element pivotally and shiftably associated with said switch operating member.

2. A device of the character described 55 comprising a pivoted control member, a pivoted switch operating member, and

means interposed between said control member and said switch operating member for controlling the snap action movement of said switch operating member in both directions when said control member is moved, said means including a spring and a shifting element pivotally and shiftably associated with said switch operating member and pivotally associated with said control member. 75

3. A device of the character described comprising a pivoted control member, a pivoted switch operating member, and means interposed between said control member and said switch operating member for controlling the snap action movement of said switch operating member in both directions when said control member is moved, said means including a spring and a shifting element pivotally and shiftably associated with said switch operating member and pivotally associated with said control member, and said spring being interposed between the outer extremity of said shifting element and said control member. 80

4. A device of the character described comprising a pivoted control member, an arm projecting therefrom, a pivoted switch operating member, and means interposed between said control member and said switch operating member for controlling the snap action movement of said switch operating member in both directions when said control member is moved, said means including a link pivoted to said arm and a spring secured to the outer extremity of said link and to said arm. 85

5. A device of the character described comprising a pivoted control member, an arm projecting therefrom, a pivoted switch operating member, and means interposed between said control member and said switch operating member for controlling the snap action movement of said switch operating member in both directions when said control member is moved, said means including a link pivoted to said arm, a spring secured to the outer extremity of said link and to said arm and means for associating said link with said switch operating member to permit of a relatively longitudinal sliding movement between said link and operating member. 90

6. A device of the character described comprising a pivoted control member, an arm projecting therefrom, a pair of push buttons for operating said member swingingly associated therewith, a pivoted switch operating member, and means interposed between said control member and said switch operating member for controlling the snap action movement of said switch operating member in both directions when said control member is moved, said means including a link pivoted to said arm, a tension spring 100

105

125

130

connecting the outer extremity of said link with said arm and means for associating said link with said switch operating member to permit of a relatively longitudinal 5 sliding movement between said link and operating member.

7. A device of the character described comprising a pivoted control member, a pivoted switch operating member, means interposed between said control member and said switch operating member for effecting the snap action movement of said switch operating member alternately in both directions when said control member is moved, 10 said means including a spring interposed between said control member and said switch operating member, and means whereby said control member causes initial movement of said switch operating member from either 15 of its alternative positions to the other.

8. A device of the character described comprising a pivoted control member, a pivoted switch operating member, and means interposed between said members for 25 providing snap action movements for said switch operating member in both directions upon movement of said control member, comprising a member pivoted to said control member and mounted for longitudinal sliding movement relative to said switch operating member, and means exerting a pull on said last mentioned member toward said control member.

9. A device of the character described comprising a pivoted control member, a pivoted switch operating member, and means interposed between said members for providing snap action movements for said switch operating member in both directions upon 30

movement of said control member, comprising a member pivoted to said control member and mounted for longitudinal sliding movement relative to said switch operating member, and a spring secured to said last mentioned member and to said control member 40 exerting a pull on said last mentioned member toward said control member. 45

10. A device of the character described comprising a pivoted control member, a pivoted switch operating member, and means interposed between said members for providing snap action movements for said switch operating member in both directions upon movement of said control member, comprising a member pivoted to said control member and mounted for longitudinal sliding and pivoted movement relative to said switch operating member and a tension spring connecting the pivots of said control member and said last mentioned member. 50 55 60

11. A device of the character described comprising a pivoted control member, a pivoted switch operating member, and means interposed between said members for providing snap action movements for said switch operating member in both directions upon movement of said control member, comprising a spring interposed between said control member and said operating member having a sliding connection therewith and 65 means on said control member engaging said operating member to give an initial movement to said operating member from either of its positions toward the other 70 thereof. 75

In witness whereof, I hereunto subscribe my name this 5th day of April, A. D. 1921.

DAVID D. GORDON.
